UNITED STATES PATENT OFFICE.

FRANK J. SMITH, OF SAN FRANCISCO, CALIFORNIA.

CAN-HEAD-SEAMING MACHINE.

1,034,373.

Specification of Letters Patent. Patented July 30, 1912.

Application filed September 12, 1911. Serial No. 648,849.

To all whom it may concern:

Be it known that I, FRANK J. SMITH, a citizen of the United States, residing in the city and county of San Francisco and State 5 of California, have invented new and useful Improvements in Can-Head-Seaming Machines, of which the following is a specification.

My invention relates to that class of machines, especially adapted for use in canneries, by which the top-heads are placed upon and "double-seamed" to the upper ends of filled cans.

The object of my invention is to provide 15 a simple and effective machine for this purpose, and to this end my invention consists in the novel constructions, arrangements and combinations which I shall hereinafter fully describe and claim, by reference to the accompanying drawings, in which—

Figure 1 is a front view of my machine. Fig. 2 is a vertical sectional view of the machine, taken in a plane at right angles to the view of Fig. 1. Fig. 3 is a view, enlarged, 25 showing the can with applied head, clamped and held at rest for the impending operation of the seaming rolls. Fig. 4 is a sectional view, enlarged, taken on the line A—B, of Fig. 2. Fig. 5 is a detail plan view, enlarged, 30 of the can-head feed-mechanism. Fig. 6 is a sectional view of the same on the line x—x of Fig. 5. Fig. 7 is a sectional view, enlarged, taken on the line C—D of Fig. 2; this figure also showing additionally 35 the inleading power shaft with its worm, for driving the main shaft of the machine. Fig. 8 is a detail plan view of the cam operated connections for operating the can-head feed mechanism. Fig. 9 is an elevation, 40 enlarged, of the seaming-head. Fig. 10 is a plan of the same, with the upper parts omitted. Fig. 11 is a fragmentary sectional view of the can-head feed mechanism on the line y—y of Fig. 5.

The frame of the machine is composed of 45 the pedestal 1 and its superstructure 2.

Supported by the frame is the inleading can-way 3' of the fixed can-supporting table 3, from which table on the opposite side 50 extends the outleading can-way 6. Through the table 3 operates the head 4 of the plunger 5, the head being normally on a level with the table, as shown in Fig. 2.

The cans 7 are fed into the machine from 55 the inleading can-way 3' by the fingers 8, as shown in Fig. 4, which are carried by the

traveling chain 9, and are diverted outwardly from the machine to the outleading can-way 6, by the deflecting rail 10, Fig. 4.

In suitable bearings 11, in pedestal 1 of the frame is mounted a rotatable shaft 12, best seen in Fig. 2. This shaft 12 carries a can-clamp, disk 13, which has its periphery formed with a series of semi-circular notches 14, shown as four in number in Fig. 4. This clamping disk 13, also has V notches 14' in its periphery seen best in Fig. 4 and will be explained later. As one of these notches 14' register the entrance of the inleading can-way 3', a can is pushed along said way by the finger 8 and as the can begins to enter notch 14 the clamping disk 13 begins to revolve, and the can carried by the finger 8 is gradually placed in notch 14 without having slackened its forward motion, the can making but one stop from the time it is placed in the can-way 3' until the cover is seamed to the can, this stop being where the seaming takes place, thus preventing the loss of liquid from the can caused by the sudden starting and stopping as in most other machines, designed for doing this class of work. The shaft 12 also carries, at its upper end, a can-head table 15, which as shown in Fig. 4, is a disk with four holes 16, the 75 inner semi-circumference of each of which holes vertically registers with one of the notches 14 of the can-clamping disk 13.

By reference to Fig. 6, it will be seen that the hole 16 of the can-head table has a ledge 90 17 upon which the flange of a can-head 18 rests, whereby said head is temporarily supported in the table. When this particular head has been moved by the table 15 to that station at which the can has entered a notch 95 of the can-clamping disk 13, said head will lie directly above said can, in the relative position shown in Fig. 6.

The means for successively feeding the can heads 18 to their seat 17 in the hole 16 100 of the can head table 15, are shown in Figs. 1 to 6, and in Fig. 11.

Rising from a pivoted table 19, supported by pillars 20 of the frame pedestal 1 are three equidistant posts 21, set in a circle and 105 forming a housing for the column of can heads as shown in Figs. 1 and 2. The can heads rest upon one another in vertical series, the base of the column lying within an aperture 22, in table 19 as seen best in Fig. 6. In the table 19 at four equidistant points are mounted slide rests 23, set ra-

dially to the aperture 22 and adapted to be projected into and to be withdrawn from the circumference of said aperture. These slide rests are assembled in diametrically opposite pairs and the functional points or inner projecting ends of one of these pairs is in a higher plane than those of the other pair; the difference being the thickness over all of the can-head. When the lower pair of these slide rests 23, are projected into the circumference of the aperture 22 of table 19, the column of can heads rests upon them. When by the rotation of the can-head table 15, one of its holes 16, comes to rest and registers under the aperture 22 in the pivoted table 19; the lower pair of slide rests 23 are withdrawn, and at the same time the upper pair are projected with the effect of dropping the lower can-head into the hole 16 in which it rests on the ledge 17 as shown in Fig. 6, and of catching and supporting the column of can-heads as is indicated by the dotted line on the left side of Fig. 6, though it is to be noted that the slide-rest indicated by this dotted line is not correct in the circumferential position shown, its true position being one at right angles. It is thus shown merely to indicate the relative projection and withdrawal of the two slide-rests. Now, immediately reversing the relative movement of the slide-rests, by withdrawing the upper pair and projecting the lower pair the whole column of can heads descends and is supported upon the lower slide-rests ready at the next step of the operation to feed a head again.

The plunger 5 has its head 4 fitted to it as shown in Fig. 3 by a yielding connection which is effected by stem 24 of said head 40 telescoping the tubular upper end of the plunger and resting on the spring 25. When the can head supported in table 15 and the can supported by the table 3 are advanced by the rotation of the table 15 and 45 the can-clamping disk 13 and the finger 8 to a position of rest directly under the seaming head; and upon the plunger head 4, the presser plate 26, in Fig. 3, actuated by the stem 27, the lever 94, roller 97, cam 98 deploys into the head, and the plunger head 4 raises and lifts the can into the can-head. The presser plate 26 at this point begins to raise and the plunger moving still higher lifts the can with its head held firmly in 55 place out of and above its rest in the can-head table 15, as shown in Figs. 2 and 3, to a position to be operated on by the seaming rolls.

As the can begins to rise with the upward movement of the plunger 5, a semi-circular clamping jaw 28, which is the complement of the semi-circular notch 14, and also the V notches 14', by which one side of the can is embraced, moves from the position shown 65 in Fig. 2 toward the can until the can is per-

fectly seated in the clamping disk 13 and the V notches on the clamping jaw are loosely seated in the V grooves in the clamping disk, but not so tight that the can will not easily slide through. At this point the roll 66 reaches the perpendicular part of the cam track 67. The plunger continues to rise to its full height, but just before reaching its highest point, the V shaped roller 72 enters the V shaped groove in the adjustable support 70, held rigidly in the frame by the jam nuts 69, as seen in Fig. 3, and the clamping jaw 28 is forced against the clamping disk 13, the can is rigidly held between them and prevented from rotating when the seaming rolls are applied. The V roll 72 entering the V groove in the support 70 and the V's on the clamping disk 28 entering the V notches on the clamping disk 13 assure a correct alinement.

The seaming device, as seen in Figs. 2, 3, 9 and 10 comprises the head 29, to which is imparted a continuous rotary movement. In this head are journaled, at diametrically opposite points, as seen in Fig. 10, the short rock shafts 30, the lower ends of which have clamps 31, in the free extremities of which are carried the grooved seaming rolls 32. When these rolls are thrown inwardly by the rocking of the shaft 30, they press upon and bend inwardly the flanges of the head and can body and affect the double seaming in the general manner, well known to the art.

When the seaming is completed the rolls swing outward, and the plunger 5 descends to its normal lower position. The next movement of the can-clamp disk 13 carries the can from the plunger head 4 to the table 3 again, and said can is directed to the out-leading can-way 6 by the rail 10.

From the foregoing description the operation of the machine will now be understood. It will be seen that, assuming intermittent motion, that is, a cycle with stated period of rest, a can-head dropped from the column, is carried by the can-head table 15 to a position at which a can enters into registering notch 14 of the can-clamp disk 13. The next movement carries the head and can to the next station, where during the period of rest from rotary motion the can is lifted into the head, is pushed up farther with its head into the plane of action of the seamer rolls, is there clamped rigidly circumferentially against rotation, cover and can being held firmly together by the pressure of the upper plunger head 26 and the lower plunger head 4, and when this clamping and holding of the assembled heads and cans is complete, the revolving seamer rolls perform their function of double seaming. When this is done, the headed can is lowered. If the can sticks to the presser plate 26, as is often the case, the underside of the

clamping jaw 28, Fig. 3, acting as a positive extractor forcibly removes the can, thus preventing stoppage, and by the next revolving movement is carried to its discharge.

5 With these parts and their operations thus made clear, the operative connections will now be described.

Referring to Fig. 2, power is led into the machine by the shaft 32. In the frame is mounted the vertical main shaft 34, from which all movements, except the rotation of the seamer head, are derived. This main shaft 34 is given motion through a worm 35, shown in Fig. 7, on the inleading power shaft 33, which worm meshes with a worm gear 36, seen in Fig. 2, secured to said main shaft. The can-clamp disk 13 has imparted to it an intermittent rotary movement, by the following mechanism: Referring to Figs. 2 and 7, the lower end of the shaft 12 which carries the disk 13, has mounted upon it an intermittent gear 37, the teeth of which are here divided into four equal sections, separated by concave-face locking-segments 38. Upon a short countershaft 39, is mounted a mutilated pinion 40, the toothed portion of which is adapted to engage with the toothed sections of the gear 37, and its smooth portion is adapted to fit 25 and engage the concave locking segments 38, of said gear. It will be seen that by the proportions indicated in Fig. 7, the gear 37 will be moved through arcs of rotation, with intervening periods of rests in which it is 30 locked by the engagement of the smooth portion of the pinion 40 with the concave segments 38 of the gear. Motion is transmitted to the pinion 40, as shown in Fig. 7, by means of a sprocket 41 on the counter-shaft 39, the chain 42, and the sprocket 43, on the main shaft 34. The can-feed fingers 8 by which the cans are pushed into the notches of the can-clamp disk 13, are driven as follows. These fingers are carried by a 45 chain 9, one end of which, as shown in Fig. 4, is mounted upon a terminal sprocket 44, on a countershaft 45. This shaft carries a sprocket 46, from which a chain 47 passes to a sprocket 48 on the main shaft 34.

50 The can-head feed operating mechanism is best seen in Figs. 5, 6 and 8. The slide rests 23 which by their projection and withdrawal control the can-head column and the feeding of the lowermost head to the can-head table, are provided each with a stud 49. These studs play in cam slots 50 made in an oscillatory ring 51 which is seated upon the pivoted table 19 by a mounting adapting it to be oscillated. The cam-slots 50 in the ring are so shaped as shown in Fig. 5, that when said ring is moved in one direction, one pair of slide-rests will be withdrawn and the other pair projected and vice versa, with the effect heretofore described. The ring 51 is oscillated by means

of a section of teeth 52 on its periphery with which meshes a toothed sector 53 carried on the upper end of the rocking pintle 54, which passes down through the hollow pillar 20. On the lower end of the pintle 54 is a crank 55 seen in Fig. 8, to which is connected a rod 56. The other end of the rod 56 is connected with a forked sliding piece carrying a roller 57, which plays in the cam 58 mounted on the main shaft 34.

The plunger 5 is lifted and lowered by the means shown in Fig. 2. 59 is a lever pivoted at 60. One of the ends of the lever is connected with link 61, which is connected with the plunger 5. The other end of the lever has a roller 62, which plays in a cam 63 on the main shaft 34.

The clamping jaw 28 is operated by the means shown in Figs. 2 and 3; said clamping jaw has a projection 64, which at its lower end is pivotally connected at 65, to the plunger 5. Above this pivotal connection the projection 64 is provided with a guide roller 66 which plays in a fixed cam-way 67 on the frame of the machine. As the plunger 5 rises from the position in which it is shown in Fig. 2, it will carry the guide roll 66 and its clamping jaw 28 with it, and as the roller 66 travels up the incline of the cam-way 67, said clamping jaw will be swung inwardly and up to the can, as is shown in Fig. 3. The extent of this pressure may be determined by adjusting the bolt 68. The seaming head 29 is carried by shaft 73 which is mounted on a frame and to which continuous rotation is imparted by the bevel gear 74 on its upper portion and the bevel gear 75, on the power shaft 33, as seen in Figs. 1 and 2. Mounted to slide vertically upon the shaft 75 is a shifting head 76, which has on opposite sides the vertical ways 77, shown in Figs. 2 and 3, and in dotted lines in Fig. 9. The seaming-head 29 has side brackets 78, in the upper ends of which are rock pintles 79. Secured upon these pintles are cranks 80 in the outer ends of which are rollers 81, which play in the vertical ways 77 of the head 76.

From the above arrangement it will be understood that during the down stroke of the head, 76, the roller, 81, will ride upon the upper walls of the guide-way 77, and into the vertical portion of this guide-way describing a circular path and that in the return movement of the head, 76, the roller 81, will come in contact with the lower wall of the guide-way, 77, and thus assume the position shown in Figs. 2 and 3.

Upon the rock pintle 79 are also secured the downwardly extending cranks 82, the lower ends of which are forked over studs 83, as seen in Fig. 3. These studs are secured to bearings 84, which are connected with sliding sleeves 85, Fig. 10, mounted in bearings 85' on the upper surface of the

seaming head 29, said sliding sleeves being mounted upon rods 86', which rods are connected at relatively opposite ends, to the cranks 86 on the upper ends of the rocker shafts 30 of the seaming head. These rods have secured upon them at each end, a nut 84', with which the ends of the sleeves contact, thereby moving said rods. It will now be seen that as the shifting head 76 is raised 10 and lowered the seaming rollers will be thrown outwardly and withdrawn by the rocking of the shaft 30. The limits of the throw of the rollers may be varied by adjusting the nuts 84' on the rods 86'.

15 The shifting head is moved up and down by a lever 87, pivoted in the frame 88. One end of this lever is forked and pivotally connected to a roller which plays in annular groove 90, in the shifting head 76. 20 Its other end has a roller 91, which plays in the cam 92 on the main shaft 34.

The upper plunger head 26 has its stem 27 passing up through and slidably movable in the shaft 73 of the seaming head 29, and 25 said plunger head stem 27 projects from the top of the machine, as seen in Figs. 1 and 2.

Pivoted in a bearing 93 on top of the frame is a lever 94. One end of this lever is pivotally connected with the stem 27, and 30 made adjustable by the jam nuts 95. At its other end the lever 94 has a roller 97 which plays in a cam 98, on the upper end of the main shaft 34. The table 19 supported by the pillars 20 is pivoted at the left side, 35 shown at 19' Fig. 1; the other side being held in place by a nicely fitted screw, and by removing this screw the plate 19 can be swung back permitting free access to the seaming head and rolls, and then swung 40 into place again without throwing anything out of adjustment.

Having thus described my invention, what I claim and desire to secure by Letters Patent is—

45 1. In a can-head seaming machine, the combination of a peripherally, notched disk for moving the cans through the machine, means for intermittently rotating said disk, said means including an intermittently revolving shaft upon which the disk is mounted, co-acting arms by which the cans are received from the in-leading can way, and delivered to the disk grooves, and a clamping mechanism to secure the cans in the disk 50 grooves, said mechanism including a semi circular clamping jaw, and mechanism by which it is closed when the can and the can head are in line.

60 2. In a can-head seaming machine, the combination of a fixed table and intermittently, rotating peripherally, notched disk for moving the cans over the table, a vertically movable plunger for lifting the cans from the table to assemble the heads therewith, and a clamping jaw thrown into action by 65 the rising plunger to grip the cans in the notches of the disk.

3. In a can-head seaming machine, the combination of a fixed table and intermittently, rotating, peripherally, notched disk 70 for moving the cans over the table, a vertically movable plunger for lifting the cans from the table to assemble the heads therewith, a clamping jaw thrown into action by the rising plunger to grip the cans in the notches of the disk, and means for varying the pressure of said clamping jaw on the can.

4. In a can-head seaming machine, the combination of a fixed table and intermittently, rotating, peripherally, notched disk 80 for moving the cans over the table, a vertically movable plunger to lift the cans from the table to assemble the heads therewith, a clamping jaw thrown into action by the rising plunger to grip the cans in the notches of the disk, said clamping jaw having a pivotal connection at its lower end with the plunger; and a fixed cam-way acting on said clamping jaw to swing it as it moves with 85 the plunger.

5. A can-head seaming machine, including a fixed table and intermittently rotating, peripherally, notched disk for moving the cans along the table, a vertically movable 90 plunger for lifting the cans from the table to assemble the heads therewith, a clamping jaw thrown into action by the rising plunger to grip the cans in the notches of the disk, a lever carrying at its upper end said 100 jaw, and having a pivotal connection at its lower end with the plunger, a fixed cam-way acting on said lever to swing it as it moves with the plunger, and a presser stop against which the upper end of the lever 105 contacts, whereby the clamp is held rigidly to the can.

6. A can-head seaming machine, including a fixed table, an intermittently, rotating, peripherally, notched disk for moving the 110 cans over the table, a vertically movable plunger for lifting the cans from the table to assemble the heads therewith, a clamping jaw thrown into action by the rising plunger to grip the cans in the notches of the 115 disk, said clamp having a pivotal connection at its lower end with the plunger, and a roller movable in a fixed cam-way acting on said jaw to swing it as it moves with the plunger, a presser stop against which the 120 upper end of the jaw comes in contact whereby it is held rigidly to the can, and means for adjusting said stop to vary the grip of the jaw on the can.

7. In a can-head seaming machine, the combination of a fixed table and intermittently, rotating, peripherally, notched disk for moving the cans over the table, a can-head table above, intermittently rotating in unison with the notched disk and having 125 130

seats for the can-heads registering vertically with the notches of the disk, a vertically movable lower plunger for lifting the cans into the can-heads, a vertically movable upper plunger to press down on the can-heads against the upward pressure of the lower plunger, and a supplemental jaw thrown into action by the rising of the lower plunger to grip the cans in the notches of the disk.

8. A can-head machine, comprising a fixed table and intermittently, rotating, peripherally, notched disk for moving the cans over the table, a can-head table above, intermittently rotating in unison with the notched disk, and having seats for the can-heads registering vertically with the notches of the disk, a vertically movable lower plunger for lifting the cans into the can-heads and projecting the upper portion of the can with its fitted head above the surface of the can-head table, a vertically movable upper plunger for pressing down on the can-head against the upward pressure of the lower plunger, a clamping jaw thrown into action by the rising lower plunger to grip the cans in the notches of the disk, and a revolving roll for seaming the flanges of the head and can when held above the can-head table.

9. In a can-head seaming machine, the combination of means for assembling the can and its head, means for clamping the can against rotation on its axis, a continuously rotating seamer head, rock shafts carried by the head, cranks on the lower ends of the rock shafts, grooved seaming rolls carried by said cranks, cranks on the upper ends of said rock shafts; sliding members connected with said upper cranks, said members having studs, forked cranks engaging said studs, rock-pintles carried by the seamer head and upon which the forked cranks are secured, other cranks secured to

said rock-pintles and having rollers projecting from them, and a vertically movable shifting head having ways engaging the rollers of said cranks, whereby the cranks are raised and lowered to transmit power to throw the seaming rolls to and from their work.

10. In a can-head seaming machine, the combination of means for assembling the can and its head, means for clamping the can against rotation on its axis, a shaft supported in the machine, a seamer head carried by the lower end of the shaft, means for continuously rotating said shaft, rock shafts carried by and passing through the head having lower cranks and upper cranks, grooved seaming rolls carried by the lower cranks, sliding members on the head connected with the upper cranks of the rock shafts, said members having studs, rock-pintles carried by the seamer head, bell cranks secured to said rock-pintles with forked ends engaging the studs of the sliding members and the other ends having rollers, a shifting head carried by and vertically movable upon the shaft which carries the seamer head, said shifting head having ways which the rollers of the bell cranks engage and having also a peripheral groove; a pivoted lever having a roller engaging said groove, and means for swinging said lever whereby the shifting head is raised and lowered to transmit power to throw the seaming rolls to and from their work.

In testimony whereof I have hereunto set my hand in the presence of two subscribing witnesses.

FRANK J. SMITH.
